UNITED STATES PATENT OFFICE.

CHANDOS ROY DIMM, OF MUNCY, PENNSYLVANIA.

GRAIN-SCOURER.

1,148,298.

Specification of Letters Patent. Patented July 27, 1915.

Application filed October 8, 1913. Serial No. 794,103.

To all whom it may concern:

Be it known that I, CHANDOS ROY DIMM, a citizen of the United States, residing at Muncy, in the county of Lycoming and State 5 of Pennsylvania, have invented certain new and useful Improvements in Grain-Scourers; and I hereby declare that the following is a full, clear, and exact description thereof, reference being had to the accompanying 10 drawings, which form part of this specification.

This invention relates to grain scouring machines of that class in which a rotating scouring cylinder is arranged within a cylindrical casing, and the object of the present invention is to provide such machines with novel means for regulating and controlling the amount of scouring action upon the grain passing through such machine. 15

In the accompanying drawings I have illustrated one practical embodiment of the invention as applied to a machine of the horizontal type; and to more readily explain the invention I will describe such embodiment in detail, so that those familiar with the art will be able to understand the invention and adapt it to scouring machines of various types. 20

The essential features of the invention and 30 the novel construction of the parts for which protection is desired are set forth in the claims following such description.

In said drawings—Figure 1 is a horizontal transverse section through a scouring machine equipped with my novel regulator. Fig. 2 is an enlarged transverse sectional view of the regulator section of the casing detached. Fig. 3 is an enlarged face view of the regulator valve. Fig. 4 is an enlarged 35 view of part of the regulator casing section. Fig. 5 is a section on line 5—5, Fig. 3.

The scouring casing is usually cylindrical in cross section, and may be of any suitable construction. In the example shown it is 45 formed of an annular series of longitudinal vertical sections 1 which are provided with ears 1^a at their meeting edges by which they are united together by means of tie-bolts 1^b. One of the ordinary sections of this casing 50 is replaced by a section 4 which contains the scouring regulator that embodies the present invention and will be more fully explained hereafter. The scouring casing, in the example shown, is supported in any suitable 55 manner, and in a preferably horizontal position, in a frame 7, of suitable construction.

Within the scouring casing there is a scouring cylinder, which may be composed of disks 2 mounted on a shaft 2^a and provided with peripheral lugs or ribs 2^b to 60 which are bolted the scouring blades or brushes 3, that may be of any desired construction, and are usually arranged tangential to the disks so that when the cylinder is rotated said blades will have a tendency to 65 throw the grain forcibly outward against the inner wall of the casing. The general construction and operation of the casing and cylinder are well known and need no further description herein. 70

The regulator section 4 above referred to may be provided with lugs 4^a which are bolted to the lugs 1^a of the adjacent sections 1, and the section 4 thus forms a portion of the casing. This section 4 is preferably located at a point above the axis of the scouring cylinder, and is chambered on its inner face and within this chamber is a longitudinally disposed regulating plate 5 that is curved in cross section corresponding approximately to the curvature of the inner 80 wall of the casing; and said plate 5 is provided at its rear side, near its upper edge, with lugs 5^b that are perforated for the passage of a hinge-rod 5^c which rod engages 85 corresponding lugs or openings 4^c in the ends of the section 4 near the upper edge thereof, so that the regulating plate 5 can be swung by rocking said shaft so as to move the lower end or edge of the plate to or 90 from the scouring cylinder. The inward swing of the regulating plate may be limited by suitable means, a stop-lug 5^d being shown on the upper edge of the plate adapted to engage a corresponding abutment 4^d on the 95 adjacent side of the section 4; see Fig. 2.

The shaft 5^c extends outside of the machine and may be provided with any suitable means whereby the shaft can be rocked and locked so as to adjust and hold the regulating plate 5 in any desired position. As shown in the drawings a slotted sector 6 is secured to the outer end of the shaft 5^c, and the slot in the sector is engaged by a bolt 6^a fastened to the frame, and provided with a 100 wing-nut 6^b by which the sector can be clamped to hold the regulating plate in any desired position. 105

A filler 4^m may be placed in the section 4, adjacent the hinged edge of the regulating plate, to prevent the grain from passing over the hinged edge of this plate into the cham- 110

ber in section 4. Any grain that might pass into this chamber behind the regulating plate can escape back into the casing at the lower edge of the section 4.

5 One of the novel features of the invention is the peculiar formation of the inner surface of said regulating plate. As shown, it is provided on its inner face with transverse ribs 5ⁿ, which extend circumferentially 10 of the scouring casing, and are preferably inclined at an angle to the perpendicular, this inclination being, from top to bottom, toward the feed end of the machine. The sides of these ribs 5ⁿ adjacent the feed end 15 of the machine are preferably serrated or ratcheted, as at 5°, the serrations or ratchets pointing downwardly. Preferably the inner face of the regulating plate is also longitudinally serrated or ratcheted between the 20 ribs as at 5°, such serrations or ratchets 5^p also pointing downwardly. Said plate also preferably has at its end, adjacent the feed end of the machine, a head flange 5^t, which is preferably slightly deeper than the ribs 5ⁿ 25 and will prevent the grain which may be directed forwardly by the first rib 5ⁿ from flying too far back toward the feed.

Operation: When the machine is to be operated the regulating valve is adjusted so 30 that its inner surface practically forms part of the inner scouring wall of the casing, and when the scouring cylinder is rotated the grain is thrown outwardly by the blades against the casing, and owing to the inclination of the blades the grain is gradually directed rearwardly toward the discharge end 35 of the machine. Some grain requires more scouring than others and where an increased scouring effect is desired the regulator 40 is adjusted farther inward so that the ribs 5ⁿ more fully engage the grain and owing to their inclination such ribs will retard the passage of grain and direct it toward the feed end of the machine, and consequently the grain will be subjected a longer 45 time to the scouring action of the machine, and the scouring can thus be regulated by adjusting the regulating-plate toward or from the scouring cylinder.

50 The regulating-plate can be adjusted entirely out of the path of the grain, as indicated in dotted lines in Fig. 1, if only very light scouring is required; or by adjusting the regulating-plate fully inward the greatest 55 scouring effect can be produced because in such position the retaining ribs 5ⁿ have full effect upon the grain and most effectively retard the passage thereof through the machine. The ratcheted surfaces of the ribs 60 and of the inner face of the regulating-plate enhance the scouring effect of the regulating plate upon the grain.

When the regulating plate 5 is moved inward or toward the revolving cylinder the 65 area or space between the corrugated sur-

face of such plate and the cylinder is reduced so that the grain is brought into closer contact with the beaters on the cylinder and is therefore scoured much harder or more thoroughly between the scouring cylinder 70 beaters and the longitudinal ribs on the regulating plate; and when the regulating plate is moved outwardly the scouring action is lessened. Thus by properly adjusting the regulating plate the grain may be scoured to 75 any desired extent.

What I claim is:

1. In a grain scouring machine, the combination of a casing, an adjustable regulating plate extending longitudinally of the 80 casing and provided on its inner face with ribs adapted to direct the grain toward the feed end of the machine.

2. In a grain scouring machine, the combination of a casing, a regulating plate extending longitudinally of the casing and provided on its inner face with inclined ribs 85 adapted to direct the grain toward the feed end of the machine.

3. In a grain scourer, the combination of 90 a casing and a scouring cylinder, an adjustable scouring regulating plate provided with ribs upon its inner face extending circumferentially of the scouring cylinder and adapted to direct the grain toward the feed 95 end of the cylinder.

4. In a grain scourer, the combination with a casing and a scouring cylinder, of an adjustable regulating plate provided with ribs upon its inner face extending circumferentially of the scouring cylinder and inclined toward the feed end of the machine, substantially as described.

5. In a grain scourer, the combination of 105 a casing, a scouring cylinder, a hinged plate provided with transversely disposed ribs upon its inner face extending circumferentially of the scouring cylinder, said ribs being parallel and inclined to direct the grain toward the feed end of the machine. 110

6. In a grain scouring machine, the combination of a casing, an adjustable regulating plate extending longitudinally of the casing and provided on its inner face with inclined ribs adapted to direct the grain toward 115 the feed end of the machine, said ribs being ratcheted on their sides toward the feed end of the machine.

7. In a grain scourer, the combination with a casing and a scouring cylinder, of a 120 scouring regulator comprising a hinged plate provided with transversely disposed ribs upon its inner face extending circumferentially of the scouring cylinder and adapted to direct the grain toward the feed end of the cylinder, said ribs being parallel and inclined toward the forward end of the machine, and means for adjusting the plate toward or from the cylinder.

8. In a grain scourer, the combination of 125

a section adapted to be inserted in the scouring casing, an adjustable regulating plate in said section provided with ribs curved circumferentially of the casing and adapted 5 to direct the grain back toward the feed end of the casing.

9. In a grain scourer, the combination of a casing and a scouring cylinder, with a scouring regulator comprising an adjustable plate provided with transversely disposed ribs upon its inner face extending circumferentially of the scouring cylinder and adapted to direct the grain toward the feed end of the machine, and with a head 15 flange on its end adjacent the feed end.

10. In a grain scourer, the combination of a section adapted to be inserted in the upper part of the casing, a regulating plate hinged in said section and provided with 20 ribs curved circumferentially of the casing and adapted to direct the grain back toward the feed end of the casing, and with a head flange on its end adjacent the feed end of the casing.

25 11. A grain scourer regulator comprising a section adapted to be inserted in the casing, a regulator plate provided with ribs curved circumferentially of the casing and

adapted to direct the grain back toward the feed end of the casing, said regulating plate 30 and casing having abutting portions to limit the inward movement of the regulating plate, and means for adjusting said regulating plate.

12. In a grain scourer, the combination 35 of a regulator comprising a section adapted to be inserted in the forward part of the casing, a regulator plate hinged in said section and provided with ribs curved circumferentially of the casing and adapted to direct the grain back toward the feed end of the casing, said plate having a ratcheted inner surface, and said ribs being ratcheted on their faces adjacent the feed end of the machine, said regulating plate and casing 40 having abutting portions to limit the inward movement of the regulating plate, substantially as described.

In testimony that I claim the foregoing as my own, I affix my signature in presence 50 of two witnesses.
